UNITED STATES PATENT OFFICE

2,627,371

ENGINE COMPRESSOR CONTROL

Antonio Bernal, Sante Fe, Argentina

Application July 15, 1947, Serial No. 761,058

4 Claims. (Cl. 230—41)

1

This invention relates to apparatus for converting one or more cylinders of an internal combustion engine into an air compressor.

In my prior patent application, Serial No. 706,412, filed October 29, 1946, now abandoned, of which the present application is a continuation-in-part, there is described an apparatus for converting one or more cylinders of an internal combustion engine to act as cylinders of an air compressor. In this apparatus there is provided a two-way valve in the portion of the intake manifold communicating with said cylinders whereby when the valve is in one position, communication between the cylinders and the carburetor is shut off, and the intake ports of the cylinders are placed in communication with an air supply duct. In the other position of said two-way valve the communication of the intake ports of the cylinders with the air supply duct is cut off and communication between said cylinders and the carburetor is re-established. There is also provided a valve associated with the head of the cylinder or cylinders which serves as a compressed air discharge valve. The compressed air discharge valve also includes a valve for closing off the discharge valve when the cylinders are operating as cylinders of an internal combustion engine.

The apparatus also includes a unitary control for simultaneously actuating both of said valves so that when the cylinders are operating as cylinders of an engine the two-way valve will be in a position to admit fuel mixture to the intake ports of the cylinders and to close off the compressed air discharge valve. When the unitary control is actuated to convert the cylinders into cylinders of a compressor, the fuel mixture is shut off from the intake ports of the cylinders and said ports placed into communication with an air supply duct. Simultaneously, the compressed air discharge valve is rendered operative so that compressed air can be discharged therefrom.

Some automotive engines require pneumatic devices for brake operation and other functions which devices use up the compressed air provided by the aforesaid mechanism; hence, the compressed air supply requires continual replenishment. Thus it is desirable not to rely upon conscious manual operation of the control rod to convert an engine cylinder from power to compressor operation, but to make such conversion automatic, dependent on an operational condition.

2

The object of this invention is to provide apparatus to convert one or more cylinders of an internal combustion engine to act as cylinders of an air compressor including a two-way valve operable to cut off the supply of fuel mixture to the cylinders and admit a supply of air to said cylinders, a compressed air discharge valve operable to be sealed when the converted cylinders are reconverted to cylinders of an internal combustion engine and an automatic control device for simultaneously actuating said valves whereby said cylinders are operated as cylinders of an internal combustion engine when the engine is under load and will operate as compressor cylinders when the engine is operating under no load or a reduced load.

The automatic control device of this invention is of very simple construction and in its preferred form comprises a cylinder with a thimble reciprocable therein, said thimble having a rod extending outside the cylinder and operatively connected at its outer end to the control rod of the compressor converter mechanism. The inner side of the thimble is acted upon by a helical spring inside the cylinder which urges said thimble towards one end of the cylinder, while the other end of the cylinder is connected by a tube to suction produced by the engine. When the suction operating under the thimble is sufficient to overcome the thrust of the spring, the thimble moves away from the opposite end of the cylinder thereby operating the converter mechanism to produce compressor action in the engine, but when the engine suction is reduced, the spring returns the thimble to its original position thereby actuating the converter mechanism in the opposite direction and restoring the engine to normal operation.

In order to facilitate an understanding of the present invention, reference is made to the accompanying drawings, in which:

Figure 1 is a side elevational view partly in section of an internal combustion engine equipped with the apparatus of the present invention.

Figure 2 is a plan view of the engine shown in Fig. 1 with some of the parts removed to facilitate a showing of the inventive features.

Figure 3 is another plan view somewhat similar to that of Fig. 2 and showing parts in section.

Figure 4 is an enlarged detailed vertical sectional view of a portion of the engine cylinder head and the compressed air discharge valve.

Figure 5 is an enlarged detailed sectional view of the automatic control device showing its connection with the carburetor.

As shown in the drawings, the engine block 1 is provided with a plurality of cylinders 2 equipped with pistons 3. The cylinder block is provided with an intake manifold 4 and an exhaust manifold which is not shown.

Intake or fuel mixture manifold 4 communicates through an induction conduit 41 provided with a throttle 42 with a carburettor 40 which is supplied with air through an air pipe 43 equipped with an air filter 38.

A head 5 is mounted in the usual manner on the upper portion of the block 1.

Cylinder head 5 is provided with a threaded opening 8 in addition to the opening for the spark plug 6 over each of the cylinders that is to be converted to a compressor cylinder. Openings 8 are surrounded by recesses 7. Each threaded opening 8 affords access to the upper portion of the cylinder 2 and receives the compressed air discharge valve 9. As best shown in Fig. 4, valve 9 comprises an outer casing or housing open at its upper and lower ends and threaded at its lower portion 10 for reception in opening 8.

A tubular shut off valve body 15 is mounted in the bore 14 of casing 9 and is provided with a head or flange 18 on its lower end adapted to engage a plane surface or seat 11 formed on the lower end face of casing 9.

Body 15 is provided with an externally threaded upper portion 16 for the reception of a closure member 26. A coil spring 12 surrounds the body 15. One end of spring 12 bears on the upper end face of the casing 9 and the other end of spring 12 bears against the under side of closure member 26 thereby urging the body 15 upwardly and the flange 18 toward its seat 11.

Control of the axial position of body 15 within casing 9 is effected by radially extending pins or studs 13 which are threadedly mounted in the wall of casing 9 and project into helical grooves 25 in the outer cylindrical surface of the body 15. Upon rotating the body 15 within casing 9 the body is axially shifted to move the flange 18 onto and off of its seat 11. Rotation of the body 15 is effected by arm 28 mounted on closure 26. A control or actuating rod 30 is connected to the free end of arm 28 to move the same. An arm 29 is also carried by closure 26 and is movable therewith.

When the valve body 15 is shifted to its lower position the air compressed in cylinder 2 is forced between the flange 18 and seat 11 and thence radially inwardly through passages 24 into a chamber 23 in the lower interior portion of the tubular valve body 15.

It will be noted that a conical valve seat 20 is provided in the lower interior portion of body 15 and that a valve body 21 of polygonal exterior formation and a conical end is pressed onto the seat 20 by a coil spring 22. Valve body 21 when seated prevents air being drawn into the cylinder 2, but air may be discharged from the cylinder 2 against the action of spring 22. Thus, when the arm 28 is rotated to shift the tubular body 15 downwardly to move disc 18 away from seat 11, air will flow through the passages 24 into chamber 23 about discharge valve body 21, up through tubular body 15 and through the hose nipple 27 to a point of use.

In order to avoid the intake of fuel mixture into those of cylinders 2 that are being used as compressors, the intake manifold is provided with valve means for closing off communication between the cylinders being used as compressors and the carburettor. When the intake manifold

is cut off, air should be supplied to the intake ports of the compressor cylinders and when the cylinders are being used as engine cylinders, the air should be cut off and fuel mixture supplied to the admission ports.

According to this invention a two-way valve 33 is provided for control of both the fuel mixture flow and air flow. As shown, particularly in Fig. 3, the valve 33 comprises a housing interposed in the manifold 4 between one of the end cylinders 2 of the block and the remaining cylinders. In addition to the ports of valve 33 communicating with the portions 35 and 35a of manifold 4 said valve is provided with two ports spaced 90° from the first ports. One of the latter ports communicates with air duct 37 which supplies filtered air, and the diametrically opposite port communicates with conduit 36, the other end of which communicates with the portion of manifold 35a adjacent the engine block.

A plug 34 having a passage 34a therethrough is mounted in the casing for rotation so that the passage 34a can be brought into register with the portions 35 and 35a of manifold 4 to place said portions in communication or be brought into register with ducts 36 and 37 to place them in communication with each other. Rotation of plug 34 is effected by a stem 34b which carries an arm 32 on its upper end.

Synchronization of the actuation of valves 15 and 33 is produced by connecting the arm 32 to arm 29 by a link 31. This connection is such that when the flange 18 is moved away from its seat 11, plug 34 is rotated to close communication between portions 35 and 35a of manifold 4 and to establish communication between conduits 36 and 37. When valve 9 is actuated to close the flange 18 on its seat 11, plug 34 is rotated to disconnect conduit 36 from 37 and connect the sections 35 and 35a of manifold 4.

While control of the valves 9 and 33 can be effected manually, the present invention provides mechanism for automatically actuating the valves in accordance with the load on the engine. Automatic operation is effected by providing a valve control cylinder 44 having a thimble like piston 45 slidably mounted therein. A piston rod 46 extends from one end of the piston through a packing gland 47 in one end of the cylinder and is connected by a coupling 48 to the valve actuating rod 30.

Coil spring 49 has one end positioned within the thimble like piston 45 and its other end bears against the head end 50 of the cylinder thereby urging the piston 45 toward the right of Fig. 5 and shifting the valves 9 and 33 to the position shown in Fig. 3 wherein all cylinders operate as engine cylinders.

As shown, the head end 50 is connected by tubing 51 to the induction duct 41 at a point just on the posterior or engine side of the throttle butterfly valve 42 when the latter is closed. When so connected, opening of the throttle 42 to the dotted line position will greatly reduce the suction exerted on piston 45 and enable spring 49 to shift the piston 45 to a position to in turn shift the valves 9 and 33 for engine operation of all cylinders. On the other hand, when the throttle valve 42 is closed, considerable suction is exerted on piston 45 and it will be drawn to the left of Fig. 5 against the action of spring 49.

Cylinder 44 may be supported by brackets 52 or by any suitable means.

While packing has not been shown between

piston 45 and its cylinder 44 nor between valve body 15 and its casing 9, it should be understood that if needed it may be employed.

For purposes of simplicity and convenience, valve 33 has been shown with four ports. However, a three port valve constructed so that manifold section 35a can be connected either with section 35 or with fresh air duct 37 may be used.

Also, the air conduits 36 and 37 and the manifold sections 35 and 35a can be controlled by independent valves actuated in synchronism.

The apparatus described serves effectively to automatically change one or more cylinders of an internal combustion engine from engine driving cylinders to air compressing cylinders when the load on the engine is low. On the other hand when a load is placed on the engine and all cylinders are needed for driving the engine, the valves 9 and 33 are shifted to make all the cylinders operate as engine driving cylinders.

Changes in constructional details may obviously be made without departing from the spirit of the invention or the scope of the appended claims.

Having now described my invention, I claim:

1. Mechanism for converting at least one engine cylinder of an internal combustion engine having a carburetor and an intake manifold for use as an air compressor comprising in combination, a compressed air delivery duct communicating with the interior of the engine cylinder to be converted, a check valve in said duct, a cylinder valve adjacent the cylinder and duct for opening or closing communication with the duct and cylinder, a fresh air intake, a two-way valve arranged in the manifold to connect the cylinder to be converted alternatively to the carburetor for power operation or to the fresh air intake with shut-off from the carburetor for compressor operation, mechanical connections for simultaneously operating the two-way valve and the cylinder valve so that when the cylinder valve is open the two-way valve admits air to the conversion cylinder only from the fresh air intake and when the cylinder valve is closed the two-way valve admits fuel mixture through the carburetor and intake manifold to said cylinder, and automatic means connected to the mechanical connections and the intake manifold responsive to fuel demand to convert the cylinder from a compressor to power operation when the load of the engine increases.

2. Mechanism according to claim 1, in which the automatic means includes a pressure respon-

sive means operable by the suction in the intake manifold to actuate the mechanical connections.

3. Mechanism according to claim 1, in which the automatic means includes a pressure responsive means operable by the suction in the intake manifold to actuate the mechanical connections, said responsive means including a piston and cylinder with the piston connected to the mechanical connections and the cylinder in communication with the intake manifold.

4. Mechanism for converting at least one engine cylinder of an internal combustion engine having a carburetor and an intake manifold for use as an air compressor comprising in combination, a compressed air delivery duct communicating with the interior of the engine cylinder to be converted, a check valve in said duct, a cylinder valve adjacent the cylinder and duct for opening or closing communication with the duct and cylinder, a fresh air intake, a two-way valve arranged in the manifold to connect the cylinder to be converted alternatively to the carburetor for power operation or to the fresh air intake with shut-off from the carburetor for compressor operation, and mechanical connections for simultaneously operating the two-way valve and the cylinder valve so that when the cylinder valve is open the two-way valve admits air to the conversion cylinder only from the fresh air intake and when the cylinder valve is closed the two-way valve admits fuel mixture through the carburetor and intake manifold to said cylinder.
